UNITED STATES PATENT OFFICE.

FRANCIS C. SANFORD, OF BRIDGEPORT, CONNECTICUT, ASSIGNOR TO THE CINCINNATI MILLING MACHINE COMPANY, OF CINCINNATI, OHIO, A CORPORATION OF OHIO.

GRINDING MACHINE.

Application filed August 24, 1922. Serial No. 583,969.

This invention pertains to machines for grinding with precision, and polishing or finishing, objects of circular cross section, including bodies of cylindrical and others of 5 tapered or conical form. The purpose of the invention is to provide an efficient machine of simple construction, adjustment and operation, capable of producing various bodies, whether cylindrical or tapered, of predetermined 10 dimensions, of true circular cross section, and with straight and true surfaces from end to end.

These objects are attained by the construction illustrated in the accompanying drawings which show one embodiment of the invention, but it is to be understood that variations of the structure may be made within the scope of the invention and as may be required or suggested by different conditions 20 and uses.

In the drawings—

Figure 1 is a broken plan view of the machine with the guards of the grinding and the second wheel removed.

Figure 2 is an elevation of the machine partly in section at the line 2—2 of Figure 1, and broken away.

Figure 3 is a detail perspective view, partly broken away, of the assembled slides and parts carried thereby.

Figure 4 a detail perspective view of the work rest preparatory to assembly.

Figure 5 a detail perspective view of the members by which the blanks or objects 35 ground are moved over the active surface of the grinding wheel.

Figure 6 a detail elevation, partly broken away, showing the push or thrust fingers of said members in proper position relative to 40 a blank to be ground with the latter supported on the work rest.

Figure 7 is a view similar to Figure 6, but omitting the work rest and showing said fingers provided with conical points to enter 45 seats or depressions formed in the ends of the blank.

Figures 8 and 9 are views similar to Figure 6, but showing more particularly how the thrust fingers are utilized to position the blank or work along the incline of the work rest in grinding tapered blanks.

Figure 10 is a detail broken plan view showing the position of parts when the blank

has been carried partway across the face of the grinding wheel.

Figure 11 is a section at line 11—11 of Figure 1, and showing more particularly the relative positions of the work guide guards, the thrust fingers and work rest with respect to the blank.

Figure 12 is a detail broken plan view showing the position of parts immediately after a blank has been delivered in proper position between the thrust fingers, and

Figure 13 is a broken plan view showing 65 a modified form of my invention in which the swinging carriage is omitted and the second wheel journaled directly upon the secondary slide.

Similar numerals of reference denote like 70 parts in the several figures of the drawing.

In centerless grinders in which the blank is operated upon by the peripheral surfaces of a grinding and a secondary wheel on opposite sides of the work, the axes of the two 75 wheels are usually placed and maintained in parallel planes which are commonly vertical; but in the present machine provision is made for bringing the plane of the axis of the secondary wheel into or carrying it out of 80 parallelism with that of the grinding wheel axis, depending upon whether it be desired to grind to true cylindrical or to tapered or conical form. If the conical form is desired the angular relation of the axes is made 85 to correspond with the desired angularity or degree of taper of the finished product, but for cylindrical grinding the axes are maintained in parallel planes. The periphery of the secondary wheel is spaced from the periphery of the grinding wheel a distance determined by the diameter or diameter and taper which it is desired to give to the finished work. The work is introduced longitudinally between the peripheries of the 90 grinding and second wheels from either side, or alternately from opposite sides.

The speeds of the grinding wheel and the second wheel may be varied as desired by the employment of driving and driven pulleys, gearing or the like, of proper relative sizes, and this will depend in greater or less degree upon the nature of the material operated upon. In this machine provision is made for advancing or axially moving the 105 blank or work by means independent of or

other than the grinding wheel and secondary wheel, or either of them.

In order to explain clearly the nature of the invention, I have illustrated and will describe the same as especially adapted for grinding rolls for anti-friction or roller bearings, but it will be understood that such machine may be employed for grinding bodies of circular cross section, whether plain or tapered, and that it is immaterial whether these surfaces are identified with roller bearings or not.

1 is the bed of the machine having dovetailed ways 2, extending lengthwise of the same on which is arranged the primary slide 3. 4 is the secondary slide which operates on dovetailed bearings *a* transversely disposed at the rear or inner end of the slide 3, so that it will be readily understood that 20 the latter carries the slide 4, while the slide 4 itself may be reciprocated in a direction transverse to that in which the slide 3 moves.

Journalized on the slide 3 is a horizontally disposed worm wheel 5 which meshes with a worm 6 also journalized on the slide 3 and having its shaft 7 provided with a suitable pulley wheel 8, Fig. 1, which latter is operated in the manner hereinafter to be described.

30 9 is a link bar or lever having an elongated slot 10, the outer end of which bar is pivoted at 11 to the slide 3 while the inner end of the bar is pivotally connected to the slide 4 by means of a stud 12 which extends through an elongated slot 13 in the bar, this kind of pivotal connection being well known and being utilized to prevent binding at the pivotal point.

Extending eccentrically from the face of 40 the worm wheel 5 is a stud 14 which passes loosely through a block 15 which latter extends up within the slot 10.

As the worm wheel 5 is rotated owing to its connection with the worm 6, the rotary 45 travel of the eccentric stud 14 will effect an oscillation or swinging movement of the bar 9, and this will cause a longitudinal reciprocation of the slide 4 transversely of the slide 3. This movement just described is a well known mechanical one and will apparently require no further description.

The worm wheel and worm and bar are protected from dirt and other foreign matter by means of a cover 16 which is secured 55 to the slide 3, and to the outer end of this cover is fastened a screw shaft 17, which has a threaded engagement with a nut 18 which latter is swiveled within a bearing support 19 that is secured to the bed plate, and rigidly secured to this nut is an operating hand wheel 20.

60 The inner end of the nut 18 is radially flanged, and the hub of the hand-wheel 20 is of larger diameter than the body of the nut, and when secured upon the outer end

thereof forms a shoulder which, with the radial flange, precludes endwise movement of the nut. Rotation of the hand-wheel in one or the other direction will cause rotation of the nut, and longitudinal movement of the screw-shaft 17 and consequently of the primary slide 3, with the parts carried thereby. This adjustment is for the purpose of determining the distance between the peripheral faces of the wheels through which the grinding is effected.

Pivoted at 21 upon the slide 4 as shown in Fig. 3, is a carriage 22 at the ends of which are curved elongated slots 23 through which extend bolts 24 that have threaded connection with the slide 4, the object of these slots and bolts being to secure the carriage 22 in any of the adjustments to which it is swung.

25 are ways secured to or formed upon the upper surface of the carriage 22, and 26 is a bearing block slidable on said ways and having at each end a slot 27 with a bolt 28 passed therethrough and screwed into the carriage for the purpose of securing the block in its adjusted positions.

29 are the bearings for the shaft 30 of what will hereinafter be referred to as the second wheel 31 these bearings being secured to the block 26 by bolts 32, as seen in Figs. 1, 2 and 13.

33 is the grinding wheel the shaft 34 of which is journalized within bearings 35 that are secured directly to the bed plate 1, and on this shaft is the usual power pulley 36, 100 for connection with motive power.

Also secured upon the shaft 34 is a pulley 38 which connects with the pulley wheel 8 by means of any suitable belt 39, and an ordinary slack-taker 40 is arranged at the side of the bed 1 for taking up the slack in the belt 39 incident to the movements of the primary slide 3, all as shown in Figs. 1 and 2.

The rotation of the secondary wheel 31 is controlled by means of any suitable belt (not shown) around the power pulley 41, on the shaft 30, and in this connection attention is called to the fact that the speed of the grinding wheel 33 is much greater than that of the second wheel 31. As seen in Figs. 1, 2, 10, 12 and 13, 43 is the work rest block which has a stud 44 projecting from the lower face and seated within an orifice 45 in the carriage 22, so that it will be clear that this block is capable of swinging movements, and at the ends of the block are curved slots 46 through which bolts 47 extend from the carriage whereby this block may be secured in any of its swinging adjustments.

As will be understood upon reference to Figs. 4, 6, 8 and 9, a work-rest 49 is pivoted at 48 to the vertical face of the block 43. The ends of this rest are provided with slots

50 curved concentrically with the pivot 48, through which slots extend bolts 51 entering tapped holes in the face of block 43, said bolts serving to clamp and hold the 5 work-rest in any position to which it may be tilted upon or about said pivot 48.

This rest is located immediately below the space which separates the grinding wheel and the second wheel, and the blanks to be 10 ground are delivered directly upon the rest in the manner hereinafter to be described.

Since in the present structure the second wheel is in no sense a feed wheel, because it does not feed the work to be ground transversely across the face of the grinding wheel, means are provided whereby such axial travel of the blank is effected and this means will now be described.

52 are push fingers having outwardly extending tails 53 and bases 54 which latter are secured directly upon and to the slide 4 by means of bolts 55 passing through elongated slots 56 in said bases and entering tapped holes in the slide 4, as seen in 25 Figs. 1 and 2 and 10 to 12. It will thus be clear that these fingers may be spaced apart more or less by means of the adjustment afforded by said slots and bolts.

The blanks to be ground are delivered 30 upon the work rest 49 between these fingers 52 the latter having been previously adjusted to accommodate the length of said blanks, and since said rest and fingers are bodily carried by the slide 4 it will be clear that 35 the blanks will be pushed bodily endwise by means of these fingers during the traversing movements of said slide, and in this connection attention is called to the fact that these fingers are always substantially in line with 40 the work rest.

The machine illustrated in the drawing is equipped for grinding a blank at each transverse movement of the slide 4, and is therefore provided with two chutes 57 and 58, 45 for delivering the blanks to be ground, these chutes being located on opposite sides of the grinding wheel and being spaced therefrom. (See Figs. 1, 10, 12 and 13.)

During the reciprocation of the slide 4 50 the space between the fingers 52 will be brought directly opposite the delivery mouth of one of the chutes, whereupon a blank will pass from the chute into this space and upon the work rest 49, and just as soon as the reverse movement of said slide begins one of the tail extensions 53 will block the chute. As the blank thus delivered between the 55 push fingers comes opposite the space between the chute and the grinding wheel there is danger that said blank might become dislodged or fail to be properly delivered to the grinding wheel, and therefore guide guards 59 are provided on each 60 side of the grinding wheel, said guards 65 being adjustably mounted on pillars 60

that are secured to the slide 3. The adjustment of these guards is merely for the purpose of accommodating them to different sizes of blanks to be ground, such adjustment being accomplished by means of elongated slots 61 in the bases of the guards through which screws are carried directly into the upper faces of the pillars 60.

The adjustment of the block 43 is for the purpose of keeping the work-rest 49 directly below the axis of the blanks to be ground, while the adjustment of the rest is for the purpose of bringing the axis of the blank below the horizontal plane of the axis of the grinding wheel, and maintaining said axes 80 in parallelism. While I have referred to such adjustment of the work-rest as shall cause the axis of the work to be below the horizontal plane of the grinding wheel axis, I do not intend to restrict myself to such adjustment, it being advantageous under some circumstances to have the axis of the work in the same horizontal plane as the axis of the grinding wheel, or above such plane.

When the carriage 22 is swung about its 90 pivot 21 it, of course, carries with it the work-rest 49, and the latter may not under such adjustment stand immediately below the axis of the blank to be ground. In such case the block 43 will be separately adjusted to give said rest proper relative position.

When the blanks to be ground are tapered, it is necessary to adjust the second wheel 31 so that its peripheral face will conform to the angle of the taper of the blanks, and this is brought about by the swinging adjustment of the carriage 22. Accordingly it becomes necessary to make a nice adjustment of the wheel 31 so that its peripheral surface will very closely conform to this 105 taper and this adjustment is effected by the inward sliding movements of the block 26 which carries the journals of the shaft of the wheel 31.

The primary slide 3 is adjustable by 110 means of the operation of the handle 20 both to compensate for wear on the grinding and second wheels and for blanks of different cross diameters.

The operation of the machine, when provided with two delivery chutes, so that a blank may be ground at each transverse movement of the second wheel, is as follows:

Presupposing the parts to be in the position shown at Figure 12, it will be observed that the space between the fingers 52 is opposite a delivery chute 57, and that a blank has moved from this chute to a position between the fingers and against the second wheel 31. 125 The blank thus delivered is supported immediately by the work rest 49, as shown at Figure 11.

The secondary slide 4 now moves to carry the second wheel, the fingers, the work rest 130

and the blank, directly across and against the face of the grinding wheel 33, and it will be noted that during this movement of the parts the fingers and their tail extensions 53 will block both chutes, until the blank just ground comes opposite the delivery end of chute 58, at which point said blank, backed by the wheel 31, will hold back the foremost blank in chute 58 until the blank so ground passes completely beyond said chute and falls off the work-rest on the side of the rest away from wheel 31. Upon reversal of movement of the secondary slide 4 the space between the fingers 52 will again be brought opposite the delivery end of chute 58, whereupon the foremost blank therein will enter the space between said fingers and come into surface contact with the periphery of the wheel 31. Further movement of slide 4 will cause the fingers 52 to move the fresh blank transversely across the peripheral face of the grinding wheel 33, and past the delivery end of chute 57 to a point where said blank will fall from the work-rest just prior to another reversal of movement of slide 4. These operations are repeated as the slide 4 is traversed first in one and then in the opposite direction.

It will be observed that intermediate the grinding wheel and the chutes are provided the guide guards 59 which project upwardly and are in line with the peripheral face of the grinding wheel, so that these guards prevent the blanks from toppling off the work rest and also insure their delivery against the face of the grinding wheel.

It will, of course, be obvious that the two chutes are not at all necessary, and that one of them may be omitted, in which case, one of the guide guards and one of the fingers would be omitted, but since the machine has a far greater output when two chutes are employed it is preferred that the machine be constructed as shown in the drawing.

If the blanks be plain cylindrical bodies with no tapered surfaces the second wheel 31 is so adjusted that its peripheral face will be parallel to the peripheral face of the grinding wheel, the operation of the machine being precisely the same whether the blanks are tapered or not.

The mechanism heretofore described for operating the primary and secondary slides is quite ordinary, and since these slides may be operated in various ways, all of which are ordinary shop expedients, I do not wish to be limited to the employment of any particular mechanism for operating these slides.

In grinding tapered blanks the angular adjustment of the peripheral face of the second wheel is always such that when a tapered blank is in contact with said wheel and is properly supported on the work rest between the fingers, such blank will always present to the peripheral face of the grind-

ing wheel a surface that extends in a straight line across the same in parallelism with the axis of the grinding wheel.

In grinding rolls for roller bearings it is deemed desirable that the axes of such rolls should be slightly below the axis of the grinding wheel, but that the two axes should be parallel, and this is a very simple matter to provide for in the grinding of plain cylindrical roller bearings, since the work rest is merely adjusted to the proper horizontal plane. But in the grinding of rolls or blanks with tapered surfaces, the present invention is particularly well adapted for properly positioning the work, since it is merely necessary to adjust the fingers 52 so that they will normally position the blank at various locations along the inclined upper surface of the work rest as clearly shown at Figures 8 and 9, where it will be noted that the axis of the blank is always in a horizontal plane, and therefore parallel with the axis of the grinding wheel, whether the blank be at the depressed or at the elevated end of the work-rest or at any intermediate point. The elevation of the plane of the axis of the blank will, however, vary as the blank is placed nearer the lower or the higher end of the work-rest. When the fingers 52 are adjusted to bring the work to the desired point in the length of the work-rest and are clamped in such adjustment, the fingers and the work-rest move together, and the blank retains a fixed position upon the rest during the traverse and grinding of the blank.

I have shown, as the preferred embodiment of my invention, and have heretofore described, the second wheel as mounted on a carriage capable of swinging adjustments, so as to present the peripheral face of said wheel at an angle to the corresponding face of the grinding wheel. On referring to Figure 13 it will be seen that the carriage 22 may be dispensed with and the second wheel journaled in bearings that are supported directly upon the secondary slide 4, the peripheral face of this second wheel being itself beveled so as to correspond with the angular surface to be ground.

In this Figure 13, the work rest block 43 and the block 26 are supported directly upon the secondary slide 4, and the adjustments of said blocks are identical with those heretofore described in connection with these blocks. The peripheral face of the second wheel is dressed at the desired angle by the usual "diamond" tool, and the operation of the machine, with the swinging carriage thus omitted, is precisely the same as has been hereinbefore described.

It is obvious that the construction illustrated in Fig. 13 and just described may be used in the grinding of cylindrical rolls or blanks, in which case the second wheel 31 will be of cylindrical form so that its pe-

riphery shall be parallel with that of the grinding wheel 33 and with the axes of the two wheels 31 and 33.

The drawings and accompanying description thereof are based upon the preferred construction and arrangement of parts, wherein the axes of the grinding wheel 33 and second wheel 31 are in a common horizontal plane, and in stating that the axis 10 of the blank or work is maintained below the axis of the grinding wheel, the word "below" is used with reference to such relative positions of the wheel axes. A like relation of the work axis to the common plane of 15 the wheel axes will usually be maintained, whether such plane be horizontal or inclined from the horizontal, and the specification and claims are to be read with this understanding.

20 Having thus described my invention what is claimed is:—

1. In a machine of the character described, the combination of a grinding wheel; a second wheel adjustable to bring its peripheral face at will into angular or into parallel relation to the peripheral face of the grinding wheel; a work-rest; and means for traversing one of said wheels and work-rest with a blank upon it, transversely across the peripheral face of the other of said wheels in the direction of the axis of the blank.

2. In a machine of the character described, the combination of a grinding wheel; a second wheel having its peripheral face arranged in angular relation to the peripheral face of the grinding wheel; a work-rest; and means for traversing the second wheel and the work-rest with a blank upon it, transversely across the peripheral faces of the grinding wheel in the direction of the axis of the blank.

3. A machine of the character described, comprising a grinding wheel, a second wheel capable of adjustment to bring its peripheral face at an angle to the peripheral face of the grinding wheel, means for delivering blanks to said wheels, and means for bodily carrying said blanks and second wheel axially across the peripheral face of the grinding wheel.

4. A machine of the character described, comprising a grinding wheel; a second wheel adjustable to place its peripheral face at any desired angle to the corresponding face of the grinding wheel; means for feeding blanks to said wheels; and means for bodily carrying said blanks and second wheel transversely of the grinding wheel, to a point at which the blank is freed and discharged.

5. In a machine of the character described comprising a grinding wheel and a second wheel adjustable to place its peripheral face at any desired angle to the corresponding face of the grinding wheel; means for bodily moving the second wheel toward or away

from the grinding wheel to vary the space between said wheels; means for feeding and delivering blanks to and from said wheels; and means for bodily carrying said blanks and second wheel axially across the grinding 70 wheel.

6. A machine of the character described comprising a grinding wheel, a second wheel adjustable to place its peripheral face at an angle to the peripheral face of the grinding 75 wheel in the common plane of the wheel axes, and means for introducing, feeding, guiding and carrying a blank from one side of the grinding wheel to the other.

7. A machine of the character described, 80 comprising a grinding wheel carried in stationary bearings, a second wheel peripherally opposed to the periphery of the grinding wheel and journaled in bearings adjustable in the common plane of the wheel axes to 85 place its periphery at an angle to the periphery of the grinding wheel, a work support between said wheels and movable in harmony with said swinging bearings, means for delivering a blank to the work support, 90 and means for bodily shifting said second wheel and the work support with a blank upon it transversely across the peripheral face of the grinding wheel, in the direction of the axis of the blank.

8. In a machine of the character described, a grinding wheel and a second wheel peripherally opposed thereto, means for adjusting the second wheel in the common plane of the wheel axes to position its peripheral face 100 at an angle to the corresponding face of the grinding wheel, a support for the work, means for feeding the work upon said support, and means for causing said support and second wheel to move across the peripheral face of the grinding wheel in the direction of the axis of the work.

9. In a machine of the character described, a grinding wheel and a second wheel peripherally opposed thereto, means for adjusting 110 the second wheel in the common plane of the wheel axes to position its peripheral face at an angle to the corresponding face of the grinding wheel, a work support, means for delivering work thereto, conveyor fingers for 115 embracing the work at each end thereof, guide-guards adjacent the grinding wheel, and means for causing the second wheel, the work support and the conveyor fingers to move across and beyond the peripheral face 120 of the grinding wheel, in the direction of the axis of the work.

10. In a machine of the character described, a grinding wheel and a second wheel peripherally opposed thereto, means for adjusting the second wheel in the common plane of the wheel axes to position its peripheral face at an angle to the corresponding face of the grinding wheel, a chute 125 for feeding the work, a guide guard located 130

between the grinding wheel and the chute, a support onto which the work is fed, conveyor fingers for embracing the work at each end thereof, said fingers having tail extensions which block the chute at all times except when the space between said fingers is alined with said chute, and means for causing the second wheel, the work support and the conveyor fingers to move across the peripheral face of the grinding wheel, and to carry the space between the fingers to and beyond the chute.

11. A machine of the character described comprising a bed, a grinding wheel journaled thereon, a primary slide on said bed movable toward and away from said wheel, a secondary slide carried by the primary slide and movable transversely thereof, a second wheel carried by the secondary slide, and adjustable in the common plane of the wheel axes to present its peripheral face at an angle to the peripheral face of the grinding wheel.

12. A machine of the character described, comprising a bed, a grinding wheel journaled thereon, a primary slide on said bed movable toward and away from said wheel, a secondary slide carried by the primary slide and movable transversely thereof, a second wheel carried by the secondary slide, a work rest also carried by said secondary slide, conveyor fingers carried by said slide and adjustably spaced apart to receive the blanks to be ground, means for feeding said blanks onto said work rest and between said fingers, and means for reciprocating said secondary slide and the parts carried thereby transversely across the peripheral face of the grinding wheel, in the direction of the axis of the work.

13. The combination with a grinding wheel, of a second wheel in plane with the grinding wheel, having its peripheral face set an angle to the opposing face of the grinding wheel; means for holding a blank against the face of the second wheel; and means for carrying the second wheel and the blank so held axially across the peripheral face of the grinding wheel and in contact therewith.

14. A machine of the character described, comprising a bed, a grinding wheel having its shaft journaled in bearings carried by said bed, a primary slide adapted for travel on said bed and lengthwise thereof, a secondary slide adapted for travel on the primary slide and transversely thereof, a carriage pivoted on the secondary slide, a second wheel whose shaft is supported on said carriage, said wheel having its peripheral face opposed to the peripheral face of the grinding wheel, means for adjusting said carriage to place the peripheral face of the second wheel in desired angular relation to the peripheral face of the grinding wheel,

means for adjusting the primary slide to effect the proper spacing apart of said wheels, means for finally adjusting the second wheel to bring the peripheral face of the latter in close contact with the blank, a work rest carried by said carriage and located close to the peripheral face of the second wheel directly opposite said face, means for delivering blanks onto said rest and against said face, conveyor fingers carried by the secondary slide and spaced apart to embrace the blanks lengthwise, said fingers having tail extensions which block the blank delivery means at all times except when the space between the fingers is brought opposite said delivery means, and means for operating the secondary slide, whereby the blank on the work rest, backed by the second wheel, is carried by the fingers across the face of the grinding wheel in close contact therewith.

15. A machine for grinding tapered blanks, comprising in its organization a grinding wheel and a second wheel, the peripheral faces of the two wheels being opposed; means for adjusting the axis of the second wheel in the common plane of the axes of the two wheels, whereby their opposed peripheral faces are placed in angular relation one to the other; means for supporting between the opposed peripheral faces a blank to be ground; means for delivering blanks onto said support; means co-operating with said second wheel for holding a blank during the grinding; and means for bodily carrying said blank, support, and second wheel across the peripheral face of the grinding wheel with the blank in grinding contact with said face.

16. A machine for grinding bodies of circular cross section, comprising a bed, a grinding wheel journaled in bearings supported on said bed, a second wheel having its peripheral face opposed to the corresponding face of the grinding wheel, a movable carriage which supports the journals of the second wheel whereby the latter is bodily carried transversely across the active face of the grinding wheel, a work rest carried by said carriage in close proximity to the face of the second wheel, means for delivering blanks onto said rest and against the face of the second wheel, means for guiding the blanks, and means for actuating said carriage to carry the second wheel, the work rest and the blank supported thereby axially across the face of and in grinding contact with the grinding wheel.

17. A machine of the character described, comprising a grinding wheel, a second wheel capable of traversing movements athwart the face of the grinding wheel, a work rest moving in harmony with the traverse of said second wheel, means for delivering blanks onto said rest, means for causing

said second wheel, rest and blank to traverse the active face of the grinding wheel, and means for guiding said blank axially in its movement to, across and from the grinding wheel.

18. In combination with a grinding wheel and a second wheel placed in peripheral opposition, the proximate peripheral faces being at an angle one to the other; a tiltable work-rest; and a support upon which said work-rest is pivoted, said support being capable of adjustment to bring the work-rest directly beneath and parallel with the axis of a blank placed thereon, and the tilting work-rest serving when properly adjusted to support and maintain the blank with its axis parallel to the axis of the grinding wheel.

19. The combination of the grinding wheel, a vertically disposed work rest capable of swinging adjustments whereby its upper edge may so support the blank to be ground that the axis of the latter is below and parallel to the axis of the grinding wheel, means for holding said blank so that its side surfaces will always be presented to the peripheral face of the grinding wheel in contact therewith in a straight line that is parallel to the axis of said wheel, and means for causing the blank thus held to traverse said face, in the direction of the axis of the blank.

20. In a machine of the character described, the combination of a grinding wheel, a second wheel, means for spacing said wheels apart more or less, means for swinging the axis of the second wheel in the common plane of the axes of the two wheels whereby its peripheral face is presented at an angle to the corresponding face of the grinding wheel; a vertical work rest located close to the periphery of the second wheel and adjustable in a horizontal plane whereby said rest will be parallel with the axis of the blank thereon, said rest also having swinging adjustments in a vertical plane whereby the axis of the blank supported thereon will always be below and parallel to the axis of the grinding wheel, means for delivering the blanks onto said rest and against the peripheral face of the second wheel, means for guiding the blanks, and means for carrying said blanks thus supported across and in grinding contact with the peripheral face of the grinding wheel.

21. In a machine for grinding bodies of circular cross section, the combination of a grinding wheel; a second wheel peripherally opposed thereto; a rest for supporting a blank between the proximate peripheral faces of said wheels; means for delivering a blank onto said rest and holding it against said second wheel; and means for carrying the second wheel, work rest and blank axially

athwart the peripheral face of the grinding wheel and in grinding contact therewith.

22. The combination with a grinding wheel, of a second wheel whose peripheral face is opposed to the corresponding face of the grinding wheel, means for delivering and holding a blank against the face of the second wheel, and means other than said wheels for carrying the blank while thus held axially across and against the peripheral face of the grinding wheel.

23. In a centerless grinding machine, the combination of a grinding wheel and a second wheel having their peripheral surfaces opposed; a reciprocating carriage on which the second wheel is mounted and with which it moves; a work-rest or support intermediate the opposed faces of the two wheels, carried by and movable with said carriage; fingers at opposite ends of the work-rest and in substantial alinement therewith, said fingers being movable with the carriage and serving positively to advance a blank lying upon the work-rest and carry it across the peripheral face of the grinder as the carriage moves in either direction; tails or extensions in plane with said fingers and extending in a direction opposite thereto; and chutes, one on either side of the grinding wheel, each serving to deliver a blank to the work-rest when the space between the fingers registers with the discharge end of either of

said chutes, the tails or extensions serving to close the delivery ends of the chutes except at such times as escape of blanks therefrom is prevented by the blank at the moment being introduced or being carried from the grinding position to the point of discharge.

24. In a centerless grinding machine, the combination of a grinding wheel and a second wheel having their peripheral surfaces opposed, the peripheral surface of the second wheel being at an angle to the proximate surface of the grinding wheel; a reciprocating carriage on which the second wheel is mounted and with which it moves; a work-rest or support intermediate the opposed faces of the two wheels, carried by and movable with said carriage; fingers at opposite ends of the work-rest and in substantial alinement therewith, said fingers being movable with the carriage and serving positively to advance a blank lying upon the work-rest and carry it across the peripheral face of the grinder as the carriage moves in either

direction; tails or extensions in plane with said fingers and extending in a direction opposite thereto; and chutes, one on either side of the grinding wheel, each serving to deliver a blank to the work-rest when the space between the fingers registers with the discharge end of either of said chutes, the tails or extensions serving to close the delivery

ends of the chutes except at such times as escape of blanks therefrom is prevented by the blank at the moment being introduced or being carried from the grinding position 5 to the point of discharge.

25. In a centerless grinder, the combination of a grinding wheel and a second wheel arranged in peripheral opposition to each other; a carriage on which the second wheel 10 is mounted for rotation; a work-rest; fingers provided with longitudinal extensions and in substantial alinement with the work-rest, said fingers being adjustably spaced apart to permit the introduction between them of 15 a blank to be ground; chutes on opposite sides of the active peripheral face of the grinding wheel, for delivering blanks one at a time onto the work-rest and between

the fingers; guards fixed on opposite sides of the grinding wheel between the same and the proximate chutes; means for moving the carriage, second wheel, work-rest and fingers back and forth across the active face of the grinding wheel and past the guards; and means for rotating said wheels in proper direction and at suitable speed; whereby a blank is positioned upon the work-rest at one side of the grinding wheel, carried across and ground by the grinding face, and moved to a point beyond the guard and chute at 20 which it is discharged from the work-rest, this action occurring at each movement of the carriage in either direction.
